UNITED STATES PATENT OFFICE.

OLIVER F. CONKLIN, OF ANDERSON, INDIANA.

ARMATURE.

1,059,351.

Specification of Letters Patent. Patented Apr. 22, 1913.

Application filed November 5, 1912. Serial No. 739,583.

To all whom it may concern:

Be it known that I, OLIVER F. CONKLIN, a citizen of the United States, residing at Anderson, in the county of Madison and State of Indiana, have invented certain new and useful Improvements in Armatures, of which the following is a specification.

This invention relates to improvements in armatures of electric dynamos or motors, and more particularly to what are known as double-wound armatures; that is, armatures which carry double windings, each winding adapted for a different purpose and connected to a separate commutator.

The armature forming the subject matter of this invention is one which is more especially intended for use in connection with dynamos and motors particularly adapted for use in connection with motor vehicles for the charging of the battery which furnishes current for lighting purposes and for self-starting, in which the electric machine must be capable of use either as a motor or generator, depending upon the function it is performing at the time.

Heretofore, it has been common to equip the armature with two windings, connecting the windings to separate commutators for different purposes. In these prior constructions, the commutators are usually placed upon opposite ends of the armature shaft, although in some cases both commutators have been placed upon the same end of the shaft. In connection with devices of this character used in conjunction with motor vehicles for lighting and starting purposes, however, the requirements are peculiar in that it is usually necessary to have a winding of relatively small wire and large number of turns connected to a commutator for furnishing current for charging the batteries, and a winding consisting of but few turns of wire of large cross-section connected to the other commutator adapted to carry a large volume of current for the purpose of operating the machine for starting the engine of the vehicle. Good engineering would require that the heavy winding for starting the engine be connected to a large commutator, while the smaller winding could very properly be connected to a small commutator. When both commutators are placed upon the same end of the armature shaft, it is obvious that the leads of the armature winding which are

connected to the commutator located farthest from the armature, must pass through the shell of the sub-structure of the commutator which is located closest to the armature. This has heretofore been accomplished by the process of first winding the lower section of the armature and then threading the leads through holes drilled in the sub-structure or shell of the nearest commutator, which commutator must be large enough in diameter to permit these leads to pass through its shell. In this case, it is obvious that it is necessary to place the nearest commutator in position upon the armature shaft before the farthest commutator is connected up. This results in inconvenience and unnecessary expense in winding the outer coils before a test of the inner winding has been made, necessitating the removal of the outer winding in case any defect in the inner winding should be discovered.

The object of this invention is to provide means by which the inner winding, which in the present case is preferably the generator or small wire winding, can be completed, the leads put in place and soldered to their commutator and thus tested out before the other commutator is placed in position on the shaft and hence before the second winding is made.

In the accompanying drawings, Figure 1 is a side elevation of an armature embodying my improved construction. Fig. 2 is a longitudinal section on the line 2—2 of Fig. 1. Fig. 3 is a perspective view in detail of what is hereinafter called the spider. Fig. 4 is a section on the line 4—4 of Fig. 2.

Like parts are represented by similar characters of reference in the several views.

In the said drawings, 1 represents the armature shaft, having thereon any well-known form of armature 2. Located on the shaft on one side of the armature is a sleeve or hub 3 of a spider, the arms 3^a of which are equally spaced apart so as to provide a series of channels; this spider being placed upon the shaft with a press-fit or other connection so as to revolve therewith. Secured to the shaft, adjacent the spider, on the side thereof opposite the armature, is a commutator 4 of any well-known construction, the diameter of which is slightly less than the diameter of the spider as represented by the outer peripheries of the arms, this commutator being what is called the outer com-

mutator; 5 represents the inner windings, which, after being wound about the armature, are extended through the channels between the arms 3^a of the spiders and connected to the commutator 4.

Located on the arms 3^a of the spider, is what is called the inner commutator 6, of any suitable construction, and the outer windings 7, after being wound about the 10 armature over the inner windings 5, are connected to this inner commutator.

While we have shown the spider formed separately from the shaft for manufacturing reasons, yet if desired, this spider might 15 be constructed integrally with the shaft. Also, the ring of the outer commutator might be made a part of the spider, but for manufacturing reasons is preferably made separate therefrom. As a result of this 20 construction, it will be seen that the inner windings may be placed upon the armature and connected up with their commutator 4 before the inner commutator 6 and the outer windings are placed in position; the spider 25 3 furnishing channels through which the inner windings may pass and also providing a support for the inner commutator 6. The outer commutator 4, being, as before stated, slightly less in diameter than the spider, allows the inner commutator 6, after being 30 properly assembled, to be slipped readily over the same and pressed in position on the arms of the spider; it being understood, of course, that the spider is installed in position 35 upon the armature shaft before the outer commutator is placed thereon. It will thus be seen that the inner winding and outer commutator 4 may be first installed and thoroughly tested out for defects before 40 the outer winding and inner commutator 6 are installed, thus obviating the trouble and expense of disturbing any of the parts than the work already completed, in the event that any defect should be discovered in the 45 inner winding, as would be the case in

some of the prior structures heretofore referred to.

Having thus described my invention, I claim:

1. In a structure such as described, an armature and its shaft, an outer and an inner winding on said armature, two commutators, one for each winding, and a channeled support for one of said commutators on said shaft between the armature and the other commutator and adapted to receive the leads of the inner winding, said support being formed separate from the commutator supported thereby.

2. In a structure such as described, an armature and its shaft, an outer and inner winding on said armature, a channeled support on said shaft, an outer commutator on said shaft adjacent said support to which the inner winding is connected, and an inner commutator on said channeled support to which said outer winding is connected, said channeled support being constructed of a separate piece from said inner commutator.

3. In a structure such as described, an armature and its shaft, an outer and inner winding on said armature, a channeled support on said shaft, an outer commutator to which the leads from the inner winding are connected, said leads being extended through said channeled support, an inner commutator located on said channeled support but formed of a separate piece therefrom, the diameter of said outer commutator being less than the inner bore of said inner commutator, substantially as and for the purpose specified.

In testimony whereof, I have hereunto set my hand this 28th day of October 1912.

OLIVER F. CONKLIN.
